UNITED STATES PATENT OFFICE.

PER OSCAR SUNDIN, OF PROVIDENCE, RHODE ISLAND.

SURFACE-PLATE.

SPECIFICATION forming part of Letters Patent No. 326,925, dated September 22, 1885.

Application filed November 7, 1884. (No model.)

To all whom it may concern:

Be it known that I, PER OSCAR SUNDIN, a subject of the King of Sweden, residing at Providence, in the State of Rhode Island, 5 have invented an Improvement in Surface-Plates, of which the following is a specification.

My invention relates to an improvement in surface-plates or tools for testing surfaces and straight-edges for mechanical use, in which a 10 top and bottom plate are connected by means of side and end plates conjointly with interior ribs; and my invention consists in the improved diagonal arrangement of the interior ribs, as hereinafter set forth.

15 Figure 1 is a top view of my improved surface-plate. Fig. 2 is a side elevation of the same. Fig. 3 is a horizontal section taken in the dotted line X X of Fig. 2. Fig. 4 is an end elevation. Fig. 5 is a transverse section taken 20 in the dotted line Y Y of Figs. 1 and 3. Fig. 6 represents the bottom view of the plate. Fig. 7 is a longitudinal vertical section taken in the dotted line Z Z of Figs. 1 and 3.

In the accompanying drawings, K is the top 25 plate, and L the bottom plate, made of equal thickness of cast-iron, and connected to each other by means of the side plates, I I, and end plates, O O, and the thinner interior ribs, D, E, and F, cast integrally with the plates K and L. 30 The ribs E E, made thinner than the plates K and L, extend from one side to the other parallel with and near the end plates, O O, and the ribs F F F F, which connect the ribs E with the adjacent end plates, O, serve to impart the 35 required strength and rigidity to the ends of the surface-plate.

In surface-plates of large size I cast an extra rib, G, extending centrally from side to side, and parallel to the ribs E E, as shown by the 40 dotted line G in Figs. 3 and 7.

The central interior portion of the plate is occupied by the longitudinal central rib, F', and by the diagonal ribs D and D', all made thinner than the plates K and L, and cylindrical enlargements A' A' A' are formed at the 45 intersection of the rib F' and ribs D with the cross-ribs E E, such enlargements being made to extend from the top to the bottom plate in line with the axis of the studs or legs A A A, 50 which project from the bottom plate, L, and are preferably made integral with the same, but in some instances they may be screwed in.

The enlargements A' A' A' are arranged at equal distances on both the ribs E E, so that they will always coincide with the legs A, even 55 if the pattern of the lower plate is reversed in the molding.

A longitudinally-directed cylindrical enlargement, B, is made in the center of the central rib, F', in line with the rib F, and from the 60 center of the end plates, O O, holes C C are drilled into the axis of the enlargement B, the holes C C being adapted for the reception of free handles or centers, whereby the plate can be lifted either by hand or by means of hoisting machinery, and can be left hanging at any 65 required angle.

M M are the holes formed in the bottom plate, L, by the core-prints, necessary for setting the cores for the interior chambers, and for the extraction of the cores from the chambers, and the core-holes M in the bottom plate will serve for the free access of air to the interior chambers, thus securing an even temperature 70 throughout the plate, whereby the rate of contraction and expansion of the top and bottom 75 plates will be equalized.

The side plates, I I, end plates, O O, and the top and bottom plates, K and L, are to be planed over, after which the top, sides, and ends can 80 be scraped to practically plane surfaces and made square with each other, the top surface, K, being in ordinary cases the main surface to be used.

An annular depression, N, is formed in the 85 bottom plate around each of the three legs A, in order to avoid contact of the planing-tool with the legs A in planing off the surface of the bottom plate.

My improved surface-plate is thus constructed 90 so that several surfaces can be scraped on the same plate—namely, the top, sides, and ends—thereby enabling the workman to test the condition of one of the surfaces by the application thereto of a straight-edge scraped to 95 coincide with the plane of the least-worn surfaces.

In my improved surface-plate, the ribs being made slightly thinner than the planed top and bottom plates and side and end plates, a 100 uniform degree of contraction and expansion will be secured throughout the plate, as it is well known to mechanics that two pieces of cast-iron of the same dimensions, one left rough

from the mold and the other planed and finished, do not receive heat from the surrounding atmosphere or impart the same with equal facility.

5 By the employment of a properly-constructed cast-iron plate having a practically-plane surface it is practicable to make the special scraped parts of a machine long before the main body of the machine is constructed or 10 made, and to be able to engage several men on the same work, where only one man could be employed if one part should be scraped to the other.

The piece of work which is to be scraped to 15 a perfectly flat surface by means of the surface-plate should be first scraped over once before it is applied to the surface of the same, otherwise it is liable to injure the plate. The surface-plate being first slightly rubbed over 20 with red-lead the scraped piece of work is to be applied to the surface of the same, or in cases where the piece of work is too heavy to apply to the plate, the plate can be applied to the work, to show where the two surfaces touch each 25 other, and the points on the surfaces of the work, which are by this means shown to be higher than others, are to be scraped off continuously until the piece exactly fits the surface-plate.

30 By the employment of three legs, A A A, extending downward from the under plate, the air will have free passage under the same when at rest upon a suitable support, and will also have free access to the interior chambers 35 through the holes M in the bottom plate. The legs will at the same time prevent accidental

contact with an uneven and rough resting surface, which might cause injury to the exactness of the scraped surfaces of the plate.

The diagonal ribs D are located in a direct 40 line from the opposite corners of the plate, and thus cross each other at the center of the same, and the ribs D' start from the longitudinal central rib, F, and run parallel with the diagonal ribs D, until they intersect with the 45 side plates, I I, and by reason of the peculiar arrangement of the ribs D and D' the surface-plate is made to stand the severest tests with regard to its rigidity and accuracy, being far superior in this respect to the ordinary surface-plate.

I claim as my invention—

1. A surface-plate having top and bottom plates, K L, side plates, I I, end plates, O O, longitudinal rib F, parallel to the side plates, 55 diagonal ribs D D, in a line extending from corner to corner of the plate, and the ribs D' D', extending from the rib F parallel with the ribs D D, substantially as described.

2. A surface-plate, having top and bottom 60 plates, K L, side plates, I I, end plates, O O, ribs E E, parallel to the end plates, O O, ribs F F, which connect the ribs E E with the end plates, rib F', parallel to the side plates, diagonal ribs D D, in a line extending from corner 65 to corner of the plate, and the ribs D' D', extending from the rib F' parallel with the ribs D D, substantially as described.

PER OSCAR SUNDIN.
